INVENTOR

BY *Victor J. Evans*

ATTORNEY

W.M. Markward

WITNESS:

UNITED STATES PATENT OFFICE.

LEE COY FOUNTAIN, OF KINGSBURG, SOUTH CAROLINA.

FURNACE.

Application filed October 13, 1923. Serial No. 668,412.

To all whom it may concern:

Be it known that I, LEE COY FOUNTAIN, a citizen of the United States, residing at Kingsburg, in the county of Florence and State of South Carolina, have invented new and useful Improvements in Furnaces, of which the following is a specification.

This invention relates to improvements in furnaces especially adapted for use in curing tobacco and has for an object the provision of means whereby the furnace will be protected to prevent accidental fires due to the tobacco leaves becoming accidentally ignited by falling on the furnace, or from sparks rising from the furnace during the process of curing.

To this end, the invention aims to provide a furnace having a lining which will prevent the escape of sparks and which is protected so that the leaves will not come in contact with the heated lining.

With the above and other objects in view, the invention further includes the following novel features and details of construction, to be hereinafter more fully described, illustrated in the accompanying drawings and pointed out in the appended claim.

In the drawings:

Figure 1 is an elevation of a furnace constructed in accordance with the invention.

Figure 2 is a central longitudinal sectional view of the same.

Figure 3 is a transverse section.

Figure 4 is a front elevation of the furnace.

Referring in detail to the drawings, wherein like characters of reference denote corresponding parts, the improved furnace comprises a casing or lining 10, the latter including side walls, a top wall and a bottom wall. The top wall is preferably transversely curved, while the bottom wall is provided with perforations 11 which extend inwardly from one end thereof for an appreciable distance and form draft openings.

The casing or lining is provided at each end with walls 12 and 13, the former hav-

ing an opening 14 therein which may be closed by hinged doors 15, whereby the furnace may be supplied with fuel. The opposite end of the wall 13 has extending therefrom a relatively small projection 16 for connection with a flue, so as to provide an escape for the products of combustion and prevent sparks from reaching the tobacco or other combustible material. Each end wall 12 and 13 is provided with a flange, the bottom portion 17 of which acts to space the bottom wall of the lining or casing from a floor or other support, while the remaining portions 18 of the flanges are adapted to receive between them a casing or cover 19 of brick or other fire-proof material.

The invention provides a furnace which may be made of any desired dimensions and placed within a barn or similar structure for curing tobacco, without danger of fire, the fire within the furnace being effectually prevented from escaping into the barn, while leaves falling from the tobacco upon the furnace will not be ignited due to the protection afforded by the fire brick 19.

The invention is susceptible of various changes in its form, proportions and minor details of construction and the right is herein reserved to make such changes as properly fall within the scope of the appended claim.

Having described the invention what is claimed is:

A furnace embodying a metallic casing including side, top and bottom walls, a perforated section provided in the bottom wall adjacent one end thereof, end walls, said end walls projecting beyond the side and top walls to define flanges and below the bottom wall to define supports, a brick covering for the lining between said flanges and flush with the outer edges thereof, a door in one end wall and a flue extension projecting from the other end wall.

In testimony whereof I affix my signature.

LEE COY FOUNTAIN.
